UNITED STATES PATENT OFFICE.

WILLIAM H. MINER, OF CHICAGO, ILLINOIS.

RAILWAY DRAFT-RIGGING.

1,074,190.

Specification of Letters Patent. Patented Sept. 30, 1913.

Application filed February 24, 1913. Serial No. 750,163.

To all whom it may concern:

Be it known that I, WILLIAM H. MINER, a citizen of the United States, residing at Chicago, in the county of Cook and State of Illinois, have invented a certain new and useful Improvement in Railway Draft-Rigging, of which the following is a full, clear, concise, and exact description, reference being had to the accompanying drawings, 10 forming a part of this specification.

My invention relates to improvements in draft rigging for railway cars.

The object of my invention is to provide a draft rigging of efficient action and durable construction.

In the drawings forming a part of this specification Figure 1 is a side elevation partly in longitudinal section on line 1—1 of Fig. 2 of a draft rigging embodying my invention. Fig. 2 is a plan view partly in horizontal section on line 2—2 of Fig. 1.

In the drawings 3, 3 represent draft sills or parts of the car frame to which the draft rigging is attached, 4 the end sill, 5 the buffer block, 6 the draw-bar carry-iron, 7 the tie plate, 8 the draw bar, the rear end of which is received within the hollow head 9 of the draft yoke 10, and is slidably connected thereto by means of the transverse coupler key 11.

12 represents the front follower, 13 the rear follower, 14, 14 front stop members, 15, 15 rear stop members, the front stop members being provided with the front stop shoulders 16, 16, and the rear stop members being provided with the rear stop shoulders 17, 17. Secured to either draft sill is a plate 29, the said plates having at their forward ends the front limiting stop shoulders 18 and 40 at their rear ends the rear limiting stop shoulders 19.

All the foregoing parts are of well known construction.

Within the draft yoke and between the front and rear followers is disposed a friction shell 20 containing the friction mechanism 21, which comprises the friction shoes 22, 22, preferably three in number and in annular

arrangement, the wedge or spreading member 23 and the antifriction rolls 24 interposed between the wedge and the friction shoes. Seated between the friction shoes at their forward ends and the friction shell at its rear end are the springs 25 and 26. An outer spring 27 incloses the friction shell, 55 and is seated at its rear end against the rear follower 13, and at its forward end against the front follower 12.

When in normal position, as illustrated in Figs. 1 and 2 of the drawings, the front follower is disengaged from the wedge, and the spring 27 presses at both its ends against the followers. On rearward movement of the draw bar the spring 27 is compressed by the rearward movement of the front follower until the front follower 12 engages the wedge 23, when the friction mechanism comes into action, and the rearward movement of the draw bar is resisted both by the outer spring 27 and the mechanism within the friction shell 20. On forward movement of the draw bar the outer spring 27 is compressed by the forward movement of the rear follower 13 until the wedge 23 engages with the front follower 12, and thereupon the parts within the shell 20 are brought into action with the said outer spring. The parts within the shell are held in assembled condition by the connecting rod 28, the function of which is well understood. The spring 27 with the inclosed friction shell 20 is received between the followers and within the lateral opening 30 of the draft yoke, being supported therein against downward displacement by the lower limb of said yoke, 85 and maintained against lateral displacement by the bars or plates 29, 29. With this device I am enabled to secure an easy initial compression resisting movement through the resisting action of the spring 27, and a high 90 resisting capacity through the combined resistance of the parts within the friction shell and the spring 27 without the same.

I claim:

1. In a draft rigging, in combination, followers, a shell between the followers, com-

pression resisting mechanism within the shell, a spring inclosing the shell, said spring being seated between the followers.

2. In a draft rigging, in combination, followers and a shell, compression resisting mechanism within the shell, a spring inclosing the shell, said spring being forwardly seated against the front follower and adapt-

ed to yield on movement of the draw bar before compression of the mechanism within the shell.

WILLIAM H. MINER.

Witnesses:

ELEANOR L. NASH,

JOHN A. MARTINKUS.
